Primary Examiner — Susan Moon Lee(74) *Attorney, Agent, or Firm* — Marcus N. DiBuduo; Mark D. Miller**CLAIM**

I claim the ornamental design for a modular beehive, as shown.

DESCRIPTION

FIG. 1 is a front-top perspective view of my design.

FIG. 2 is a bottom plan view of the embodiment of FIG. 1.

FIG. 3 is a top plan view of the embodiment of FIG. 1.

FIG. 4 is a front elevational view of the embodiment of FIG. 1.

FIG. 5 is a right side elevational view of the embodiment of FIG. 1.

FIG. 6 is a rear elevational view of the embodiment of FIG. 1.

FIG. 7 is a left side elevational view of the embodiment of FIG. 1; and,

FIG. 8 is a front-bottom perspective view of the embodiment of FIG. 1.
